UNITED STATES PATENT OFFICE

90,924

DESIGN FOR A GOLF PUTTER HEAD

Hartley L. Replogle, Chicago, Ill.

Application August 24, 1933. Serial No. 49,103

Term of patent 7 years

To all whom it may concern:

Be it known that I, HARTLEY L. REPLOGLE, a citizen of the United States, residing at Chicago, in the county of Cook and State of Illinois, have invented a new, original, and ornamental Design for a Golf Putter Head, of which the following is a specification, reference being had to the accompanying drawing, forming a part thereof.

Fig. 1 is a front elevational view of a golf putter head embodying my new design;

Fig. 2 is a rear elevational view thereof;

Fig. 3 is an elevational view of the putter head looking at the tip of its blade portion;

Fig. 4 is an elevational view of the putter head with the hosel lying nearest the observer;

Fig. 5 is a top plan view of the putter head; and

Fig. 6 is a bottom plan view thereof.

I claim:

The ornamental design for a golf putter head as shown.

In witness whereof, I hereunto subscribe my name this 22 day of August, 1933, at Chicago, Illinois.
